G. W. COOKE,
FAUCET,
APPLICATION FILED APR. 24, 1918.
1,378,218. Patented May 17, 1921.

Inventor
George Winthrop Cooke
By his Attorney
Frank M. Farley

UNITED STATES PATENT OFFICE.

GEORGE WINTHROP COOKE, OF JAMAICA, NEW YORK.

FAUCET.

1,378,218.

Specification of Letters Patent. Patented May 17, 1921.

Application filed April 24, 1918. Serial No. 230,572.

To all whom it may concern:

Be it known that GEORGE WINTHROP COOKE, a citizen of the United States, and resident of Jamaica, L. I., in the county of 5 Queens and State of New York, has invented certain new and useful Improvements in Faucets, of which the following is a specification.

This invention relates in general to fluid 10 flow control mechanisms and is directed particularly to improvements in faucets.

My main object is to provide a faucet which shall be simple in construction, easy to make and inexpensive to manufacture.

15 As will be clear from the description the invention consists chiefly in providing means whereby the flow control valve may be easily provided with a seat therefor without necessitating any constriction in the 20 main body of the tubular inlet member, thus eliminating difficult and time consuming labor.

With these objects in view, the invention consists in the particular construction and 25 disposition of parts and the improved modifications in the old types of metal faucets as shown in the drawing and described more fully herein.

In the drawing accompanying this specification and forming a material part thereof,

Figure 1 is a longitudinal cross sectional view of my improved faucet, connected to a water supply and showing the valve closed,

Fig. 2 is a similar view with the valve 35 open,

Fig. 3 is a section taken along line 3—3 of Fig. 1, and

Fig. 4 is an end elevation.

Referring in detail to the drawing, my 40 newly improved faucet is seen to consist of a tubular casing having an inlet passage-way 10 communicating by means of the valve 11 with the outlet tube 12. The inlet tubular casing is threaded at the connecting end 45 as at 13 for the nut 14 and is further provided with a flange 15 so that the gaskets 17, 17, may be held therebetween against the wall or partition 18 through which the faucet is inserted to connect to the water supply 19. In the front end of the tubular casing 50 operates purchaser or head 20 secured against rotation in some suitable manner as by being flattenend as at 21 and adapted to be manipulated by the thumb to be pressed in against the spring 22 for con-

trolling the opening of the valve. This spring is held between the head 20 and the body of the flange 22 which is perforated as at 23 to permit the valve stem 24 to pass therethrough.

In constructions now common, the seat for the valve is provided by constricting a portion of the inlet tube. This causes much extra labor and expense and results in a very weak construction. In the embodiment 60 of my invention shown in the drawing, I provide a valve seat by means of a member 25 made of a light, inexpensive, easily worked yielding and water-tight material, such as cork. This member 25 fits snugly 65 into the inlet tube and has a thick end 26 perforated as at 27 for the valve stem and a hollow body portion 28 perforated for the outlet tube 12 and extending beyond this outlet tube. The end of the member 25 is 70 cut away at 29 to form the conical seat 30 for the valve. It will be noted that an abutting shoulder 31 is provided which abuts the end of element 25 or valve seat 30 and co-operates with the valve seat to cut 75 off the water supply and also prevents the soft material from being displaced under pressure of the valve.

It will be noted in my construction that not only does the tubular casing remain circular throughout in cross-section, but the valve head 11 when seated to close the supply rests against a soft water-tight material instead of against metal parts thus preventing the usual result in rapid wear and 85 the necessity of frequent repair.

The operation of my newly improved faucet will be clear from Figs. 1 and 2. In Fig. 1 the valve is closed and the water from the supply shut off from the outlet 95 tube. In Fig. 2 the spring has been compressed by the manipulation of the head 20. The valve is opened and the water from the source may flow over the valve into the space 33 in the hollow end of the member 100 25 and then through the opening therein out through the outlet tube 12.

Having thus described my invention, I claim as new and desire to secure by Letters Patent,

1. A faucet comprising a cylindrical tube of uniform internal diameter and having inlet and outlet openings and a valve structure comprising a tube of soft yielding material closely fitting the inner wall of said casing 110

and having a valve seat at one end and an outlet opening registering with the outlet opening of the casing, and having a central axial bore at the opposite end of smaller 5 diameter than that of the inner diameter of the said tube; and a valve located in said casing opposite said valve seat and having a stem which fits in sliding engagement in said bore of smaller diameter and extends 10 therethrough.

2. A faucet comprising a casing made of a short length of tube, and having an inlet and an outlet, and an inner tubular member made of softer material than that of 15 said casing and closely fitting the inner periphery thereof and having a valve seat formed in one end thereof; and a valve in said casing located opposite said valve-seat and provided with a valve stem which ex-

tends through said inner tubular member in 20 water tight relation with its opposite end.

3. A faucet comprising a casing made of a short length of tube and having an inlet and outlet, and a valve construction comprising 25 a tube of yielding material having a valve seat at one end and an opening registering with the outlet of the casing, the said outlet comprising a tube, one end of which extends into the opening formed in said tube of yielding material and serving to prevent 30 same from being displaced in said casing.

Signed at New York city in the county of New York and State of New York, this 31st day of March A. D. 1918.

GEORGE WINTHROP COOKE.

Witness:

JOANNA C. COOKE.
